UNITED STATES PATENT OFFICE.

RAYMOND M. MARKLAND, OF BROOKLYN, NEW YORK.

CIGAR BOX.

Application filed June 8, 1922, Serial No. 566,700. Renewed February 26, 1925.

To all whom it may concern:

Be it known that I, RAYMOND M. MARKLAND, a citizen of the United States, and a resident of the city of New York, borough 5 of Brooklyn, in the county of Kings and State of New York, have invented new and useful Improvements in Cigar Boxes, of which the following is a full, clear, and exact description.

10 This invention relates to cigar boxes.

The ordinary cigar box is provided with a one-piece lid of sufficient size to cover the whole box. When cigars are packed in such and it is desired to display them in a show 15 case of limited area it becomes necessary to remove the lid from the box. The removal of the lid from the box damages it and eliminates all means provided for retaining the cigars in the box.

20 The general object of this invention is the provision of a cigar box provided with a sectional lid, one section of which may be removed so that the open box will occupy a smaller area in a display case.

25 A further object of the invention is the provision of a cigar box having a sectional lid, one section of which may be removed from the other, provided with means for fixing the two sections of the lid together.

30 This object is accomplished by providing a body or container and a sectional lid, one section of which is hinged to the body and the other section removably attached to the hinged section, and attaching to the body 35 portion of the box a gummed sheet that may be applied to the sections of the lid rigidly attaching them together.

These and other objects of the invention will be more clearly understood from the 40 following detailed description and accompanying drawings.

Figure 1 is a perspective view of the box open;

Figure 2 is a perspective view of the box 45 closed and sealed;

Figure 3 is an end view of a portion of the body of the box showing an end view of the lid and the means of hinging it to the body;

50 Figure 4 is an end view of a portion of the body of the box with one section of the lid attached;

Figure 5 is a plan view of the plate used for connecting the sections of the lid;

55 Figure 6 is a section along the line 6—6 of Figure 5.

Referring to the above-mentioned drawings, a box body 10 is shown packed with cigars 11. The lid of the box is made up of two sections 12 and 13. Section 12 is 60 hinged to the body 10 of the box by means of a gummed fabric 14. The section 12 of the lid may be made of any fabric 14. The section 12 of the lid may be made of any desired width and the area of the display case occupied by the box will be equal to the surface area of the top of the box and the area of the section of the lid hinged thereto. Stamped on the inner face of the section 12 may be the price and the brand 70 of the cigars or any other advertising desired. If stamping is not satisfactory a sheet of paper having the above data stamped thereon may be pasted to the inner face of the section 12. Extending into the 75 section 12 from its outer edge and parallel to the top and bottom surfaces are slots 15. Slots 16 are formed in the section 13 of the lid and so located in the lid that when the two sections are fitted together the slots 80 15, 16 are in alinement. Mounted in the slots 16 of the section 13 are plates 17 which are provided with tongues 18. These tongues 18 engage the section 13 of the lid and retain the plates in position in the 85 slots 16. The plates 17 may be made of any suitable material but is preferably made from a corrugated metal sheet. When the section 13 is associated with the section 12 to form a lid, the plates 17 which have 90 been mounted in the slots 16 engage in the slots 15 and serve to detachably connect the sections together.

A sheet of paper or tinfoil is attached 95 to the body 10 of the box and serves to form a lining for the same. Attached to the body 10 of the box along the side to which the section 12 is hinged is a gummed sheet 19 of some suitable fabric. This sheet 19 serves as the cover sheet for the cigars and when it is desired to use the cigar box with the section 13 attached the sheet 19 may be torn out of the box. If it is desired to fix the two sections 12 and 13 of the lid together the gummed sheet is spread over 100 the section and attached thereto by means of the coating of gum.

In preparing this box for shipment the lid sections 12 and 13 are fastened in position, as shown in Figure 2. The seal 21 is 110 applied so that it engages only section 12 of the lid and attaches it to the body of the

box. Consequently when the box is opened and section 13 of the lid removed the whole of the seal is still attached to the box, complying with the statutory requirements of certain States.

I would state in conclusion that while the illustrated example constitutes a practical embodiment of the invention, I do not limit myself strictly to the exact details herein illustrated since manifestly the same can be considerably varied without departing from the spirit of the invention as defined in the appended claims.

Claims:

1. A cigar box, comprising a body portion, a lid made in two sections, means for hinging one section to the box portion, means for detachably connecting the other section to the section hinged to the body portion, and means provided, in conjunction with the body portion for fixing the two lid sections together.
2. A cigar box of the class described, comprising a body portion, a lid made up of two sections, means for hinging one section to the body portion, means for detachably connecting the other section to the hinged section, and a sheet of gummed paper provided in conjunction with the box for fixing the two sections together.
3. A cigar box of the class described, comprising a body portion, a lid for said body portion made in two sections, means for hinging one section to the body portion, means attached to the other section for detachably connecting it to the hinged section, and means provided in conjunction with the

body portion for fixing the two sections of the lid together.

4. A cigar box of the class described, comprising a body portion, a lid for said body portion, said lid being made in two sections, one section being hinged to the body portion and having slots provided therein, means attached to the other section for engaging in said slots to detachably connect the sections together, and a sheet of gummed paper provided in conjunction with the body portion for fixing the two sections of the lid together.

5. A cigar box of the class described, comprising a body portion, a lid consisting of two sections, means for hinging one of the sections to the body portion, said hinged sections having slots formed therein, plates attached to the other section and adapted to engage in the slots in the hinged section to detachably connect the sections together, and a sheet of gummed paper provided in conjunction with the body portion for fixing the lid sections together.

6. A cigar box of the class described, comprising a body portion, a lid made up of two sections, one of said sections being hinged to the body portion, said hinged section being provided with slots, plates attached to the other section and shaped to fit into the slots in the hinged section for detachably connecting the two sections together, and means provided in conjunction with the body portion for fixing the sections together.

RAYMOND M. MARKLAND.
